UNITED STATES PATENT OFFICE.

ANDREW MORRISON, OF PITTSBURG, PENNSYLVANIA.

TIE-PLATE FOR RAILWAYS.

No. 921,724.

Specification of Letters Patent.

Patented May 18, 1909.

Application filed May 20, 1908. Serial No. 433,966.

To all whom it may concern:

Be it known that I, ANDREW MORRISON, a resident of Pittsburg, Allegheny county, Pennsylvania, have invented a new and useful Tie-Plate for Railways, of which the following is a full, clear, and exact description, reference being had to the accompanying drawings, forming part of this specification, in which—

10 Figure 1 is a bottom plan view of one form of tie-plate embodying my invention; Fig. 2 is a longitudinal section; Fig. 3 is an end view; and Fig. 4 is an end view showing a modification.

15 My invention relates to tie-plates for railways of that class in which the plate is provided with longitudinal flanges at or near its lateral edges for the purpose of causing the plate to adhere to the tie; and is designed to 20 provide a tie-plate of this character with means in connection with the longitudinal flanges for giving the tie-plate resistance against endwise movement on the tie.

19 The precise nature of my invention will be best understood by reference to the accompanying drawings, which will now be described, it being premised, however, that various changes may be made therein by those skilled in this art, without departing from 30 the spirit and scope of my invention, as defined in the appended claims.

Referring to these drawings, the numeral 2 designates the plate, which is preferably a 35 rolled plate, provided on its lower face adjacent each edge with a deep adhesion flange 3. Extending transversely of the plate are one or more transverse ribs 4, extending at substantially right angles to the longitudinal flanges 3, and which are adapted to embed 40 themselves in the upper portion of the tie to effectively prevent any endwise movement of the plate. The sides of these transverse flanges, as well as the lateral faces of the longitudinal flanges 3, are preferably beveled, as 45 shown, although they may be of any suitable cross section.

50 5 designates a transverse shoulder upon the upper face of the tie-plate, against which the outer edge of the rail bears.

55 In the form of my invention illustrated, two of the transverse ribs 4 are shown, one inside of the rail-bearing shoulder 5, and the other outside of such shoulder. While I do not limit myself to this arrangement, it is, however, a preferable one, for the reason that

the maximum load is sustained by the tie-plate at or about the base of the shoulder 5, and by providing one of the transverse ribs 4 at either side thereof, these ribs will embed themselves equally in the tie, and thus afford 60 a maximum resistance to the lateral movement of the tie-plate.

As shown in Figs. 1, 2 and 3, the transverse ribs 4 terminate at the inner sides of the longitudinal flanges 3. In the form of 65 the invention shown in Fig. 4, however, these ribs are extended outside of the flanges 3, and thus extend substantially across the entire width of the plate. These cross ribs may, however, be of less length than the distance between the flanges 3, and any suitable number of them may be provided, distributed at the desired points throughout the length of the plate. I have found that these transverse ribs are particularly effective 70 when used in combination with the longitudinal adhesion flanges in the manner herein shown and described, for the reason that the flanges in penetrating the tie compress and confine the fibers of the tie between them, thus insuring the putting of the fibers in the best condition by increasing the density thereof to give the most effective 75 lateral resistance.

While I do not limit myself thereto, yet the 80 plate herein described is one that can be readily formed by rolling, so that it can be cheaply manufactured.

What I claim is:

1. A railway tie-plate having a deep adhesion flange adjacent to each of its lateral edges, and a lateral resistance rib extending transversely of the plate at approximately right angles to the direction of the flanges, said rib being of less depth than the flanges, 85 substantially as described.

2. A railway tie-plate having a longitudinally extending deep adhesion flange, and a transversely extending lateral resistance rib of less depth than the flange, substantially as 100 described.

3. A railway tie plate having longitudinally extending adhesion flanges on its under side, there being one of such flanges adjacent to each edge of the plate but inset inwardly 105 from the edge, and a lateral resistance rib extending transversely of the plate and connecting said flanges at their intermediate portions, said rib having its end portions of decreased depth; substantially as described. 110

4. A railway tie plate having a deep adhesion flange at each of its lateral edge portions, a transverse rail bearing shoulder on its upper surface, and two lateral resistance ribs extending transversely of the plate in substantial parallel relation to the shoulder, said ribs being of less depth than the flanges and located on the under side of the plate at

opposite sides of the shoulder, substantially as described.

In testimony whereof, I have hereunto set my hand.

ANDREW MORRISON.
